L. WEISS

AUTOMOBILE ROOF

Filed Jan. 29, 1927

Patented Oct. 9, 1928.

1,686,587

UNITED STATES PATENT OFFICE.

LEOPOLD WEISS, OF NEW YORK, N. Y.

AUTOMOBILE ROOF.

Application filed January 29, 1927. Serial No. 164,590.

This invention relates to vehicles in general and particularly to what is termed closed vehicles.

One of the objects of my invention is to provide in connection with a closed vehicle a swinging top or cover, which may readily be opened to permit unrestricted entrance into the vehicle through the open door, without the necessity of stooping, and also permitting standing up within the vehicle before sitting down or after getting up from the seat.

Another object of my invention is to provide, in connection with such swinging top, means for opening and closing the top, preferably operable from the driver's seat.

Another object of my invention is to provide, in connection with such operating means, a device for keeping the top open to any desired degree, and at the same time, preventing the top from inadvertently closing, while being brought to its open position.

Another object of my invention is to provide, in connection with such operating means, an operating member or handle which may be readily collapsed, out of the way, when not in use, and brought into operative position when desired.

The foregoing and further objects will be more fully apparent from the accompanying drawings forming part of this disclosure, but by no means intended to limit this invention to the actual showing, and by the following description.

In the drawings, Fig. 1 represents a side elevation of an automobile provided with my swinging top, in its open position,

Fig. 2 illustrates in diagrammatical manner the end view of a vehicle, provided with a swinging top,

Fig. 3 is a detail view, partially in section, showing the operating parts connected with and adapted to swing the top into open and closed position.

Fig. 4 is a cross sectional view taken on line 4-4 of Fig. 3,

Fig. 5 is a diagrammatical top view of my operating mechanism,

Fig. 6 is a detail view of a collapsible operating handle.

Fig. 7 is a cross sectional view taken on line 7-7 of Fig. 6, and

Fig. 8 shows a modified diagrammatical form of my operating mechanism.

Referring to the drawings, numeral 10 denotes a vehicle body of a closed car provided with a stationary top or roof portion 11 and a

swinging top or roof portion 12. The latter is preferably hinged to the body in the manner shown in Fig. 3, although any other construction may be provided for achieving the same purpose. The swinging top 12 is preferably provided with a peripheral rim 13 which is adapted to overlap the top edge of the body in such a manner as to permit opening of the side doors. This detail is not shown in the drawing, since it is obvious.

At the inner face of the top there are provided longitudinal guides 14 in which play slides 15, connected with levers or rods 16. The latter are preferably equipped with a substantial hub 17 which is keyed, as shown at 18, to operating shaft 19.

In Figs. 1, 2, 3, and 5, I have illustrated a sprocket wheel 20, attached to shaft 19, and driven by sprocket chain 21 from another sprocket wheel 22. The latter is keyed to an auxiliary shaft 23 upon which is also keyed a larger sprocket wheel 24. The latter is connected by sprocket chain 25 to sprocket wheel 26, associated with operating shaft 27. The latter is provided with a ratchet wheel 28, engaged by ratchet 29 which may be released or permitted to slide over the teeth of the ratchet wheel, as desired. The provision of this ratchet wheel, engaged by the pawl, assures against back slipping, and at the same time may be employed for keeping the top at a desired open position. When pawl 29 is released, the top may be lowered.

Operating shaft 27 is actuated by a collapsible handle 30 which is so constructed that it may be tipped inwards and out of the way, when desired. This is made possible by constructing the head 31 in such a way as to swing about pivot 32 passing through the head 31 and flattened end 33 of shaft 27.

The operating mechanism of my device is preferably arranged within the framework of the body and under the seat of the driver, as will be clearly seen in Fig. 1. It is desirable that handle 30 be placed in the center portion of the seat so that either the driver or any one sitting in the front seat of the car may operate the top.

In Fig. 8, I have illustrated a modified form of my operating mechanism in which operating lever 16' is shown attached to shaft 19'. The latter is operated by means of a bevel gear 34, meshing with bevel gear 35, which is driven by upright shaft 36 from bevel gear 37. The latter is engaged by bevel gear 38, to which motion is transmitted by means of

shaft 39 from bevel gear 40. The latter is driven by bevel gear 41 attached to shaft 42. This shaft is provided with collapsible handle 43. To shaft 42 there is keyed a ratchet 5 wheel 44, with which registers a ratchet 45, which is permitted to either slide over the teeth, while the top is being lifted, or which is disconnected from the ratchet wheel when the top is being lowered.

10 It is obvious, that in order to ease the closing of the top, shock absorbers of any desired design may be employed at the edge of the vehicle or at the part of the top engaging the edge, although such devices are not shown in 15 the drawing.

In Figs. 3 and 4, I have shown a detail construction of the top or roof of my device in which a waterproof covering 46 is illustrated, which is supported by a solid member 47 to 20 which is attached the upper portion 48 of hinge 49. The lower portion 50 of the hinge is attached to the upright part 51 of the vehicle.

Covering the lower hinge portion are solid 25 fillers 52 and 53 to which is attached the depending portion of cover 46. The solid portion 53 is movable up and down and is supported by spring 54. The upper edge of portion 53 abuts at 55 with the solid portion 47 of 30 the upper roof part.

This construction permits a ready opening or closing of the top without crushing or squeezing the waterproof covering 46 at the hinged part of the roof, since that covering 35 is being stretched the moment the top is in closed position, and will fold outwards when

solid portion 53 will be forced down by the solid portion 47 of the roof.

As has been said before, the drawings are intended purely for explanatory purposes 40 and therefore are not meant to limit the present invention to merely the showing. Therefore, the above explained details are not of marked importance, in view of the fact, that the broad idea of a swinging top is intended 45 to be covered by this application.

It is also obvious, that, while I have shown two mechanical ways of operating the top, pneumatic, hydraulic, or electric arrangements may be substituted for said mechanical 50 construction, without departing from the broad scope of my idea, for which I claim:—

In combination with a closed, motor driven vehicle, a hinged top portion extending from the rear of the vehicle to the driver's compartment, said top portion having peripheral overhanging edges adapted to prevent moisture from entering the interior of the vehicle, a shaft extending beneath the hinged edge of the top, a plurality of levers keyed to said shaft, a plurality of lever guides attached at the inner face of said top, the free ends of said levers provided with hinged slides adapted to register with said guides, the latter having means for preventing disengagement of said 60 slides from said guides, a hand operable drive arrangement connected with said shaft and adapted to be operated from the driver's seat.

Signed at New York, in the county of New York and State of New York, January, A. 70 D. 1927.

LEOPOLD WEISS.
